VANE PUMP ROTOR

George A. Waldie, Edison, and Johan A. Muller,
Dayton, Ohio, assignors to H-P-M Develop-
ment Corporation, a corporation of Delaware

Application October 26, 1942, Serial No. 463,336

5 Claims. (Cl. 103—136)

1

This invention relates to pump rotors and, in particular, to rotors for vane pumps. Vane pumps, as heretofore known, substantially comprise a flow control member or slide block with a cylindrical bore movable selectively into or out of a position concentric to a cylindrical body forming a part of the pump rotor and being rotatable in the cylindrical bore of the said flow control member or slide block. The cylindrical body is provided with radial slots having reciprocably mounted therein an uneven number of vanes for pumping fluid. The vanes are laterally confined and guided by two flanges, one of which is integral with the cylindrical body, whereas the other flange is connected to the cylindrical body by bolts or screws because the casting of both flanges as an integral unit with the cylindrical body would make it impossible to provide the vane slots. This known structure has not been very successful when working under high pressure, since, due to such high pressure, the screws or bolts connecting one flange to the pump rotor tend to stretch and loosen and not only cause increased leakage and thereby a material decrease in the efficiency of the pump but eventually break and damage the pump.

It has been suggested to weld the flange to the cylindrical body of the pump rotor instead of fastening the flange to the cylindrical body by screws or bolts. However, this method is likewise not satisfactory, since the local heat treatment inherent to welding causes distortion and misalignment to vital parts of the pump rotor.

It is, therefore, an object of this invention to provide an improved method of making a vane pump rotor which will overcome the above mentioned drawbacks inherent to the vane pump rotors heretofore known.

It is another object to provide a vane pump rotor which, when completed, constitutes a single integral unit.

It is a further object of this invention to provide a vane pump rotor which is composed of a plurality of parts adapted to be accurately finished individually and to be so connected as to form an integral unit.

These and other objects and advantages of the invention will appear more clearly from the following specification in connection with the accompanying drawings, in which:

Figure 1 is a section through a vane pump with a pump rotor according to a first embodiment of the invention.

Figure 2 shows the vane pump rotor of Figure 1 on a somewhat larger scale.

2

Figure 3 illustrates the method of making the vane pump rotor of Figure 2.

Figure 4 is a section through the central portion of the vane pump rotor.

5 Figure 5 shows a second embodiment of the invention.

Figure 6 is an exploded view of Figure 5.

Figure 7 is a section along the line 7—7 of Figure 5.

10 Figure 8 is a perspective front view of an element forming a part of the vane pump rotor.

Figure 9 illustrates the broaching of the vane slots.

Figure 10 shows a third embodiment of the 15 invention.

Figure 11 is an exploded view of Figure 10.

Figure 12 is a section along the line 12—12 of Figure 10.

20 Figure 13 illustrates two cooperating elements of the vane pump rotor.

Referring now to the drawings in detail and Figure 1 thereof in particular, the vane pump illustrated therein comprises a pump casing 1 having passageways 2 and 3 therethrough serving selectively as inlet and outlet channels.

25 Slidably mounted in the casing 1 and guided by guiding surfaces 4 and 5 is a flow control member 6. This member 6 has a cylindrical bore 7 cooperating with vanes 8 slidably mounted in the 30 pump rotor 9. The member 6 is provided with passageways 10 and 11 respectively communicating with the passageways 2 and 3.

The pump rotor shaft 9 is journaled in the 35 casing 1 by means of anti-friction bearings 12 and 13 and has mounted in one end thereof a driving shaft 14, which is rigidly connected to the rotor 9 so as to rotate therewith. The driving shaft 14 is hollow and has mounted therein a plunger 15 which is continuously urged toward 40 the outside by means of a spring, not shown, within the hollow portion of the driving shaft 14.

The plunger 15 engages one end of a conical pin 16, the other end of which is engaged by an 45 adjustable screw 17. The screw 17 threadedly engages a split nut 18 which is rigidly connected to the pump rotor shaft 9 and accessible from the outside after removal of a protecting cover 19 connected to the cover 20 forming a part of the pump casing.

The conical shaft 16 engages the inner edges of the vanes 8, said edges being formed in agreement with the taper of the conically shaped outer surface of the pin 16. By adjusting the screw 17, the vanes 8 can be adjusted in radial direction.

As to the detailed construction of the pump ro-

tor 9, this construction is illustrated in Figures 2, 3 and 4. As will be seen therefrom, the pump rotor 9 consists of a central hollow sleeve 21 with a hub 22. The hub 22 contains the vane slots 23 which are preferably milled therein by a cutter 24. The sleeve 21 also comprises a groove 25 on the inside thereof for receiving brazing material for the brazing operation later referred to.

After the sleeve 21 has been completely machined, the flanges 26 and 27 are mounted on the ends of the sleeve 21 so that they abut the adjacent portions of the hub 22. Thereupon, the driving shaft 14 is inserted into the interior of the sleeve 21 so that the groove 25 surrounds a portion of the shaft 14. After all parts have thus been assembled, they are rigidly connected to each other so as to form a single integral unit. This is done in a brazing furnace by the brazing operation known per se.

According to this operation, the assembly is furnace-brazed at a high temperature, in the neighborhood of 2200° F., and immediately moves to a "cooling" furnace, the temperature of which is suitable for hardening purposes. When the assembly is removed from this last mentioned furnace, it is quenched.

Referring to Figures 5 to 9, illustrating another embodiment of the pump rotor according to the invention, the pump rotor shown in these drawings and generally designated 28, comprises a central member 29 with flanges 30 and 31 adjacent the ends thereof. The vane slots 32 are broached therein as illustrated in Figure 9. The end portions of the central member 29 are engaged by slotted sleeves 33, 34. One of the sleeves, namely sleeve 33, has mounted therein the driving shaft 35, as indicated in Figure 5.

When the elements have been assembled as shown in Figure 5, they are interconnected by brazing in a brazing furnace. In this way, the rotor elements form a single integral unit. Inasmuch as, in the first and second embodiments of the invention, described above, the elements are machined separately, accurate machining of all parts and particularly of the vane slots can be carried out without difficulties, thereby obtaining great efficiency of the rotor when the latter is in operation.

Referring now to the third embodiment shown in Figures 10 to 13, the vane rotor shown therein and generally designated 36, differs from the second embodiment, just described, primarily in that the central member 37 is built up of a plurality of—in the illustrated drawing seven—wedge-shaped elements or segments 38. The sides of these segments are milled to form slots for the vanes when the segments are assembled. The ends of these segments have tongues 39 for locating them in the assembly. These tongues fit into radial grooves 40 in the flanged faces of a pair of hubs 41, 42.

Both of the hubs 41 and 42 are counter-bored from the side which has the radial groove 40 to receive rings 43 and 44. These rings provide a shoulder for locating the segments 38 in a radial direction. While such a shoulder might be provided on the hubs 41 and 42, the said shoulder would interfere with the straight-through milling of the grooves.

The flanges 45, 46 on the rotor, which form the end walls for the vanes, are made up of a pair of relatively large discs bored to fit the largest diameter of the hubs 41 and 42. These flanges are the last pieces to be assembled, their bores serving to lock the segments 38 in place against the rings 43 and 44 by fitting over the tops

of the tongues 39. The upper portion of the segments 38 provide spaced shoulders for the flanges 45, 46. When the elements just referred to have been machined and assembled in the manner shown in Figure 10, the assembly is ready for the brazing and heat treating operation.

It will be understood that we desire to comprehend within our invention such modifications as come within the scope of the claims and the invention.

Having thus fully described our invention, what we claim as new and desire to secure by Letters Patent is:

1. In a rotor for vane pumps, a hollow sleeve having an integral enlarged hub centrally of said sleeve, there being slots through said sleeve and hub radially thereof, said slots being formed to receive and guide the pump vanes, and cylindrical flange elements fitting over said sleeve and abutting opposite ends of said hub respectively, each flange element being substantially greater in diameter than said hub and adapted to abut said vanes throughout their radial range of operation, said flanges and said hub being integrally united into a rigid unit.

2. In a rotor for vane pumps, a hollow sleeve, including a hub of larger diameter than said sleeve and integral with said sleeve and forming therewith a pair of axially spaced shoulders, there being a plurality of slots through said sleeve and hub radially thereof, each slot being substantially coextensive with said hub in an axial direction, flange elements having central apertures fitting said sleeve and abutting said shoulders, respectively, said sleeve and flange elements being united into a rigid integral unit.

3. In a rotor for vane pumps, a sleeve having a hub integral therewith, said hub being of larger diameter than said sleeve and being located to form with said sleeve two shoulders separated by a distance substantially equal to the width of said vanes, slots through said sleeve and hub radially thereof, the vanes of the pump being slidably fitted in said slots, cylindrical end flanges of greater diameter than said hub, having central openings fitting said sleeve, said flanges and sleeve being integrally united with said flanges abutting respective shoulders thereby to slidably engage said vanes throughout their radial range of operation.

4. In a rotor for vane pumps, a sleeve having a hub integral therewith, said hub being of larger diameter than said sleeve and being so located thereon as to form with said sleeve two shoulders spaced apart a distance substantially equal to the width of said vanes, axial slots through said sleeve and said hub substantially radially thereof, the vanes of the pump being adapted slidably to fit said slots, cylindrical end flanges of greater diameter than said hub having central openings therein for receiving said sleeve, a drive shaft having one end shaped to fit within said sleeve, said sleeve, said flanges and said drive shaft being integrally united to form a rigid unitary rotor structure.

5. In a rotor for vane pumps, a hollow sleeve having a hub integral therewith, said hub being of larger diameter than said sleeve and being so located thereon as to form with said sleeve two shoulders spaced apart a distance substantially equal to the width of the pump vanes, axial slots through said sleeve and said hub substantially radially thereof, the vanes of the pump being adapted slidably to fit said slots, cylindrical end flanges of greater diameter than said

hub having central openings therein for receiving said sleeve, a drive shaft having one end shaped to fit within said sleeve, said sleeve, said flanges and said drive shaft being united to form a rigid unitary rotor structure, a tapered pin axially shiftable within said sleeve, said pin being adapted for engagement with the inner edges of said vanes, and means carried by said rotor for engaging and axially shifting said pin so as to radially adjust said vanes.
